UNITED STATES PATENT OFFICE.

SOCRATES A. XIPPIAS, OF BUFFALO, NEW YORK.

VERTICAL ELECTRIC FAN.

Application filed June 7, 1927. Serial No. 197,055.

This invention relates to improvements in ventilating fans of the vertical type, such as disclosed in Letters Patent No. 1,577,280, and the reissue thereof.

5 The primary object of the invention is to simplify the construction of such fans, whereby the cost of manufacture is considerably reduced and the assembly, or the removal and substitution of parts, is facilitated.

10 Fans of the type illustrated in said patents, include a spherical casing, and another object of the present invention is to form such casing of a pair of sections and to connect the sections together by novel joints, which will not alone permit ready dismantling of the casing, but which in use, will rigidly connect the parts and prevent the same from accidentally disconnecting, due to 15 vibration.

Another purpose of the invention is to furnish improved means for detachably connecting the fan casing to the motor casing, such means functioning to lock the parts 20 together, but permitting rapid dismounting of the fan casing whenever necessary.

A still further object is to furnish novel instrumentalities for detachably mounting the motor in its casing, such instrumentalities 25 preventing the motor from vibrating relatively to its casing when the fan is in use.

30 Another object is to provide novel means for detachably connecting the rheostat and control switch within the motor casing, the latter casing being so constructed that the motor, rheostat and switch may be introduced into the same from the bottom, and be readily secured in position by suitable crews or the like, the latter being freely 35 accessible to a suitable tool when the motor casing is in inverted position.

40 A still further object is to provide an improved arrangement for mounting the impeller on its supporting shaft.

45 With the foregoing objects outlined and with other objects in view which will appear as the description proceeds, the invention consists in the novel features herein set forth in detail, illustrated in the accompanying 50 drawings, and more particularly pointed out in the appended claims.

Referring to the drawings,

Fig. 1 is a side view of the fan, partly in vertical section, and with certain parts in 55 dotted lines, and other parts omitted to facilitate illustration;

Fig. 2 is a perspective view of the lower end of the fan casing;

Fig. 3 is a similar view of the upper end of the motor casing;

60 Fig. 4 is a fragmentary vertical sectional view of the lower end of the fan casing and the upper end of the motor casing, shown connected together;

Fig. 5 is a vertical sectional view of a 65 fragment of the motor casing, and an elevation of a portion of the motor showing the means for mounting the motor in the casing.

Fig. 6 is an enlarged horizontal sectional 70 view of the motor casing and motor, viewed from below;

Fig. 7 is a fragmentary detail partly in vertical section of the two sections of the 75 fan casing, and the means for connecting them together;

Fig. 8 is a perspective view of the impeller;

Fig. 9 is a perspective view of the fan 80 casing sections, showing the same dismantled; and

Fig. 10 is a vertical sectional view of the 85 hub portion of the impeller and the shaft of the latter, showing the means for connecting the impeller to the shaft.

In the drawings, 1 indicates the fan casing which is of tubular construction, flaring toward its lower end. The wall of the casing is thickened at equally spaced points to provide vertical flanges 2 which snugly engage 90 bands 3 on the motor when the latter is inserted into the casing from below. When the motor is placed in the casing, the upper shoulders 4 of the motor abut against projections 5 at the top of the casing, and the 95 motor is thus prevented from moving upwardly any further.

The lower end of the motor rests on supporting plates 6 which are connected to the under sides of the flanges 2 by means of 100 extension screws 7, the latter being readily reached from the large end of the casing, when the latter is inverted. Due to this construction, it is obvious that the motor may be quickly detached from the casing, as 105 soon as the screws 7 are removed.

Apertures 8 are provided at diametrically opposite sides of the casing, to permit access to the adjusting devices 9 of the motor brushes, (not shown).

110 The enlarged lower end of the casing is thickened internally, as shown at 10, to pro-

vide projections to receive screws 11, employed in securing the rheostat and switch assembly 12 in position.

Short legs 13 are arranged at the lower end of the casing to support the latter in an elevated position, whereby air may enter the casing from below, and pass upwardly through the latter during the operation of the fan, for cooling the motor, such air being discharged from the motor casing through the neck 14 of the latter.

It will be apparent that the screws 11 permit the ready disconnection of the rheostat and switch assembly from the motor casing.

After the motor, rheostat and switch assembly have been connected to the motor casing, the shaft 15 of the motor will project upwardly through the neck 14, and this shaft, as best shown in Fig. 10, is screw threaded at its upper end, as at 16. An impeller 17 is provided with a capped hub 18, which is threaded interiorly for connection with the screw threaded end 16 of the shaft. Arms 19 project from the hub, and the upwardly and downwardly projecting blades 20 are connected to these arms.

Before the impeller is connected to the shaft, the lower half 21 of the fan casing is connected to the motor casing, and to permit this the section 21 is furnished at its lower end with a ring 22 having at its edge, equally spaced horizontally disposed inwardly extending flanges 23. In placing the fan casing section 21 on the neck 14, the flanges 23 are aligned with the notches 24 in the external surface of the neck, and when the flanges reach the lower ends of these notches, the section 21 is turned to move the flanges 23 into grooves 25 provided in the thickened portions 26 of the neck. When the parts are moved into this position, they are locked together by some suitable fastening means such as a screw 27, see Fig. 4.

Owing to this construction, the two casings are rigidly locked together, and vibration caused by the operation of the motor will not dislodge the fan casing.

The section 21 is of semi-spherical shape and provided at its upper edge with equally spaced horizontal flanges 28, each having a lug 29 at one end.

The cover or other section 30 of the fan casing is also of semi-spherical shape, and provided at its edge with equally spaced hook-shaped projections 31, adapted to receive the flanges 28. When the flanges are threaded into the hooks 31, and the cover is turned, the parts will interlock and the lugs 29 will form stops to limit the turning movement of the section 30. As the surfaces of the parts 28 and 31 snugly engage each other, a large area of friction surfaces will be in contact and effectively prevent acci-

dental loosening of the sections of the casing. 65

The casing is provided over its entire area with air inlet openings 32, and outlet openings 33, but only a few of these openings are shown to facilitate illustration.

In the operation of the fan, the impeller 70 draws air into the fan casing through the motor casing, and through the polar intake openings 32, and it discharges this air gently through the openings 33.

From the foregoing, it will be seen that 75 I have provided a ventilating fan of the vertical type, the parts of which may be shipped in knock-down condition and be readily and rapidly assembled by unskilled workmen.

While I have disclosed a preferred embodiment of the invention, I am aware that changes may be made in the details illustrated without departing from the spirit of the invention as expressed in the claims. 80

What I claim and desire to secure by Letters Patent is:

1. In a ventilating fan, a tubular casing provided with spaced flanges extending in the direction of the axis of the casing, a 90 motor having its periphery engaging said flanges, spaced plates engaging the flanges and the motor, and screws detachably connecting the plates to the flanges.

2. In a ventilating fan, a tubular casing, 95 a motor in the casing supported from below, a rheostat and switch assembly arranged in the casing below the motor, and means accessible through the lower end of the casing for detachably connecting the motor, rheostat 100 and switch assembly to the casing.

3. In a ventilating fan, a vertically disposed tubular casing, a motor arranged in the casing, abutting against the upper end of the latter, and having a shaft projecting 105 through the upper end of the casing, supporting means in the casing on which the motor rests, and threaded members detachably connecting the supporting means to the casing.

4. A ventilating fan including a tubular motor casing flared toward its lower end, a motor of larger diameter than the upper end of the casing, located within the latter and having a shaft projecting through the upper end of the casing, movable supporting means arranged in the casing and on which the motor rests, a rheostat and switch assembly arranged in the lower end of the casing, means detachably connecting said assembly to the casing, an impeller detachably mounted on said shaft, and a sectional fan casing enclosing the impeller and detachably connected to the upper end of the motor casing. 115

In testimony whereof I affix my signature.

SOCRATES A. XIPPAS.
